UNITED STATES PATENT OFFICE

HAROLD A. DENMIRE, OF AKRON, OHIO, ASSIGNEE TO THE GENERAL TIRE & RUBBER COMPANY, OF AKRON, OHIO, A CORPORATION OF OHIO.

WATCHCASE HEATER.

Application filed February 25, 1927. Serial No. 170,826.

This invention relates to heaters for vulcanizing rubber articles and it particularly pertains to an improved form of watch case heater.

- 5 Watch case vulcanizing units of the character now generally used are usually closed by some form of mechanical screw or wedge arrangement in which the wedging surfaces come to substantially the same clamping 10 position after each operation. The screw or wedging apparatus is generally operated by an hydraulic piston arrangement. When vulcanizers of this character are used repeatedly over a long period of time the wedging 15 surfaces of the clamping members become worn at the clamping position, with the ultimate result that the vulcanizing unit must be repaired.
- The object of the present invention is to 20 provide a simple and quickly operative vulcanizing heater of the watch case type that will be independent of localized surface wear of the clamping members and that will require a minimum of repair during its 25 operating life.

An additional object of the invention is to provide a heater of the above designated character that requires very little floor space and that may be operated by less skilled 30 operators without danger of damage to the heater parts.

Figure 1 of the accompanying drawing is a side elevational view of a watch case heater constructed in accordance with the invention.

35 Fig. 2 is a transverse sectional view of the watch case heater shown in Fig. 1 taken substantially on line 2—2 of Fig. 1.

Fig. 3 is a detailed transverse sectional view of a portion of the heater showing the 40 replaceable mold shell thereof.

The watch case heater shown in the accompanying drawing comprises a heater base 1 to which is hinged the heater doors 2 and 3. Each heater door has a mold shell 45 5 mounted therein. The opposing mold shell 5 of each pair is mounted in the heater base in conventional manner.

Each mold door has a transverse rib 6 extending diametrically thereacross for receiving the mold-closing hydraulic pressure that is applied to the center of the heater door by a door closing lever 8. The lever 8 has one end pivotally mounted on the vertically arranged pintle 9 adjacent a 55 pintle supporting lug 10 that is formed on

the heater base. The other end of the lever 8 extends beyond the heater door where it is engaged by a pivoted stirrup 11 that is carried at the end of the hydraulic piston rod 12. The piston rod 12 extends through 60 a suitable packing gland 13 into an hydraulic cylinder 14 that is formed in the heater base. A suitable piston 15 is carried upon the inner end of the piston rod.

Suitable pins 17 that are respectively 65 carried by lugs 18 that are arranged on opposite sides of the levers 8 connect the lever with the door so that it may be operated therefrom.

The heater doors are pivotally supported 70 from arms 16 that are mounted on the pintle 9. The pintle 9 is supported from the heater base adjacent each end by suitable lugs 17.

The operation of the heater is particularly simple. After the mold cavity is charged, 75 the door is closed and the stirrup is swung over the end of the lever. Application of hydraulic pressure to the hydraulic piston closes the door of the heater with any desired degree of pressure. The heater door is 80 opened by releasing the hydraulic pressure and preferably applying air pressure to the opposite side of the piston to force it to its outermost position. The operating lever 8 is then released from the stirrup 11 and the 85 door swung open. The simplicity of the working parts and their independence of localized wear greatly reduces the repair and operating expense over conventional heaters.

The closing lever is pivoted concentrically 90 with the pivotal support for the door in order to avoid relative movement between the door and the lever when the hydraulic closing pressure is applied and the stirrup that engages the outer end of the lever is made self- 95 seating to insure a straight pull on the connecting rod.

It will be obvious to those skilled in the art that the closing lever may be arranged in different ways with respect to the heater door without departing from the invention. 100 It is particularly important that the closing pressure be applied substantially at the center of the heater door. It will also be obvious that the heater may be used for the 105 vulcanization of either solid or hollow objects such as vehicle tire casings, inner tubes, bead rings, etc. I desire therefore that the invention be construed as broadly as the prior art will permit.

What I claim is:

1. A watch case heater comprising a heater base, a mold shell carried by the base, a door swingably supported from the base, a mold shell carried by the door adapted to mate with the mold shell carried by the base to define therewith a molding cavity, a door closing lever pivotally supported from the base, hydraulic means carried by the base 10 for acting on the free end of said lever to close said heater, and means for releasably engaging the lever and the hydraulic means.

2. A watch case heater comprising a heater base, a mold shell carried by the base, a door swingably supported from the base, a mold shell carried by the door and adapted to mate with the mold shell carried by the base to define therewith a molding 20 cavity, a door closing lever pivotally supported from the base concentrically with the pivotal support for the door, said lever being adapted to engage the door in a zone substantially centrally arranged with respect to the molding cavity, hydraulic means carried by the base and adapted to releasably engage the free end of said lever for closing the heater.

3. A watch case heater comprising a heater base, a mold shell carried by the base, a door swingably supported from the base, a mold shell carried by the door adapted to mate with the mold shell carried by the base to define therewith a molding cavity,

and to provide between the mold shell and the door a cavity for receiving heating fluid, a door closing lever adapted to move with the door and pivotally mounted on the base coaxially with the mounting for the door, an hydraulic cylinder carried by the heater base adjacent the free end of the lever, a piston mounted in the cylinder, a readily releasable connection for joining the piston with the free end of the lever, and means carried by the door engaging the lever in a zone substantially concentric with the molding cavity of the heater.

4. A vulcanizing heater comprising a heater base carrying a mold member, a door swingably supported from the base, said door and mold member being shaped to define a molding cavity therebetween, and means arranged to cooperate with said door for closing said door against said mold member and maintaining said door against said mold member under pressure during a heating operation, said closing means comprising a lever pivoted on said base, hydraulic means carried by the base arranged to cooperate with and move said lever, and releasable connecting means intermediate said door and hydraulic means whereby said door may be moved to substantially full open position after a heating operation is completed.

In testimony whereof I affix my signature.

HAROLD A. DENMIRE.
